UNITED STATES PATENT OFFICE.

FRED ZIEGEL, OF HAZLEHURST, MISSISSIPPI.

DESIGN FOR A SUPPORT FOR CHIMNEY-CAPS.

SPECIFICATION forming part of Design No. 33,078, dated August 14, 1900.

Application filed July 10, 1900. Serial No. 23,166. Term of patent 7 years.

To all whom it may concern:

Be it known that I, FRED ZIEGEL, a citizen of the United States, residing at Hazlehurst, in the county of Copiah, State of Mississippi, 5 have invented and produced a certain new and original Design for a Support for a Chimney-Cap, of which the following is a specification, reference being had therein to the accompanying drawings.

10 Figure 1 is a perspective of a support for a chimney-cap, showing my new design; and Fig. 2 is a side elevation of the same.

As shown in the drawings, the leading or material feature of my design consists of the 15 straight portions A at opposite sides, having circular or coiled portions B at their upper ends, from which substantially-straight portions C extend to a central coiled or circular portion D. The opposite ends of the portions

A are composed of a straight portion E, ex- 20 tended substantially parallel with the portion A, and a second parallel straight portion F, terminating at its end in a point or tooth G. The straight portions A, E, and F are suitably spaced apart, as illustrated in the drawings, and at the points of bending a small loop H is formed. 25

Having described my invention, what I claim as new, and desire to secure by Letters Patent, is—

30 The design for a support for a chimney-cap as herein shown and described.

In testimony whereof I affix my signature in presence of two witnesses.

FRED ZIEGEL.
